UNITED STATES PATENT OFFICE.

THOMAS N. RUSSELL, OF CHICAGO, ILLINOIS.

CAR-COUPING-CENTERING DEVICE.

1,150,458.

Specification of Letters Patent. Patented Aug. 17, 1915.

Application filed March 19, 1915. Serial No. 15,474.

To all whom it may concern:

Be it known that I, THOMAS N. RUSSELL, a citizen of the United States, and a resident of Chicago, in the county of Cook and State of Illinois, have invented certain new and useful Improvements in Car-Coupler-Centering Devices, of which the following is a specification, reference being had to the accompanying drawings.

This invention relates to means for centering a car-coupler laterally relative to the car-body. When a car is uncoupled from the adjacent car while standing upon a curved track, the coupler is left out of its normal centered position unless some means be provided by the action of which the coupler, when released from the coupler of the adjacent car, is moved into its normal centered position relative to the car-body. When a car not provided with a coupler-centering-device, and having its coupler displaced from its normal centered position toward one side of the car, is to be coupled to another car having its coupler in normal position or out of normal position toward the opposite side of the car, it is necessary for the brakeman to force one or both of the couplers laterally so as to cause a proper engagement of the coupling-devices. Inasmuch as a coupler in ordinary use upon a freight-car weighs some three or four hundred pounds, it will be understood that under such circumstances the operation of coupling two cars is accomplished only by the exercise of considerable force on the part of the brakeman, such operation being accomplished very often with some little danger to the brakeman.

It is the principal object of my invention to provide mechanism through the medium of which when a car is uncoupled the coupler automatically moves to its normal centered position relative to the car, whether the car be upon a curved or a straight track, and whether or not the car be precisely in its normal upright position or tipped slightly from such normal position by reason of the inclination of the track.

It is another object of my invention to improve devices of this type in sundry details hereinafter pointed out.

The preferred means by which I have accomplished my objects are illustrated in the accompanying drawings and are hereinafter specifically described.

That which I believe to be new and de-

sire to cover in this application is set forth in the claims.

In the drawings,—Figure 1 is a transverse vertical section through the shank of a coupler of a car provided with my improved centering-devices, the view being taken substantially on line 1—1 of Fig. 2; Fig. 2 is a longitudinal vertical section through the parts shown in Fig. 1, being taken substantially on line 2—2 of Fig. 1; Fig. 3 is an enlarged detail, being substantially a section taken on line 3—3 of Fig. 2; Fig. 4 is an enlarged detail similar to Fig. 3 but showing the parts in a changed position; Fig. 5 is a detail taken substantially on line 5—5 of Fig. 3, but slightly reduced in size therefrom.

Referring to the several figures of the drawings, in which corresponding parts are indicated by the same reference characters,—10 indicates the end sill of a car forming a portion of the framework of the car, and 11 indicates a striking casting, said end sill and striking casting being secured by bolts or rivets in suitable position relative to the remainder of the framework. As is best shown in Fig. 1, the striking casting 11 is formed in the shape of an inverted U, to the lower ends of the arms of which is secured a carrier-iron 12. In the construction shown the carrier-iron 12 is in the form of a housing, the bottom wall of which provides a suitable support for oscillatory supporting members or cams, as hereinafter described. A coupling-device comprising a coupler-shank 13 of any approved type is movably mounted between the arms of the striking casting 11, being adapted to move laterally of the car between said two arms. The coupler-shank 13 and the striking casting 11 are provided with oppositely-disposed buffers 14—15, as best shown in Fig. 2, the buffers being adapted to limit inward movement of the coupler-shank longitudinally of the car-body.

16—17 indicate two supporting members in the form of cams or arms mounted between the laterally-extending walls of the carrier-iron 12 and adapted to oscillate laterally therebetween. As best shown in Figs. 3 and 4, the lower end of each of the supporting members 16—17 is bifurcated, providing two lugs 18—19 adapted to straddle longitudinally-extending bearing ribs 20 extending upward from the upper face of the bottom wall of the carrier-iron 12.

- A plurality of openings 21 is provided through the laterally-extending walls of the carrier-iron 12 at the lowermost portions of the housing formed by the carrier-iron 12, by reason of which openings any water, dust or other foreign elements are free to escape readily from the housing so as not to interfere with the operation of the supporting members.
- 10 The oscillatory arms or cams 16-17 have mounted upon their upper ends a bearing-plate 22, provided with depending flanges 23-24, between which flanges the oscillatory arms 16-17 have a working fit. The bearing-plate 22 is provided on its upper face with lugs 25 between which the coupler-shank 13 is adapted to be seated. The flanges 23-24 are provided with oppositely-disposed vertically-extending slots 26 in which pins 27 fixed in the cams or arms 16-17 are adapted to work.
- For retaining the arms or cams 16-17 in proper position in the carrier-iron housing, I have provided pins or rivets 28 secured in the laterally-extending walls of the carrier-iron and working in suitable slots 29 in said arms or cams. As will be readily understood, the pins 28 also serve to prevent the supporting lugs 18-19 of the arms or cams 30 from slipping out of proper operative position relative to the ribs 20.
- For holding the bearing-plate 22 with its attached arms 16-17 in proper position in the carrier-iron 12 for shipment or storage, I have provided a pin 30 passing through the laterally extending-walls of the carrier-iron and working in suitable slots 31 in the flanges 23-24 depending from the said bearing-plate 22.
- 40 By an inspection of Fig. 3, which shows the centering-device in its normal position, with the coupler-shank 13 in its normal centered position relative to the car-body, it will be seen that the upper face of the bearing-plate 22 is substantially flush with the upper edge of the laterally-extending walls of the carrier-iron 12. It will also be noted that both of the lugs 18-19 of each of the arms or cams 16-17 are in operative engagement with the bottom wall of the carrier-iron 12, and that the slot 26 and pin 27 of each arm or cam are directly over the corresponding longitudinally-extending bearing-rib 20.
- 55 With the parts in the position shown in Fig. 3, the coupler-shank 13 is free to move laterally out of the normal central position upon the application of force thereto by reason of the passage of the car over a curved track, or through any other agency. The shank 13, upon such a movement laterally relative to the car-body, carries with it the bearing-plate 22 by reason of the engagement of the lugs 25 with the shank, causing the arms or cams 16-17 to swing laterally in the same direction. As the arms 16-17 swing to the right in Fig. 3 from the normal centered position, the support of each of said arms is shifted immediately in the same direction from the two lugs 18-19 to the single lug 19. At the same time the point of engagement between the bearing-plate 22 and the curved upper end of each of the said arms 16-17 is also shifted slightly to the left, destroying the balance of the coupler upon the said arms or cams, whereby upon the release of the coupler from the influence of the force by which it was moved laterally the said coupler is caused to move to the left upon the said arms 16-17 to re-establish its equilibrium at its centered position. The curvature of the arms or cams 16-17 relative to the lugs 18-19 upon which they are rocked is such that the bearing plate 22 is caused to rise very slightly if 85 at all upon the swinging of the arms as above described. It will be readily understood that the positioning of the lugs 18-19 relative to each other and the curvature of the cams 16-17 are to be coördinated in such a 90 way that the coupler will be returned to its normal position relative to the car-body regardless of any normal inclination of the car-body due to unevenness of the track or to the inclination or banking of the track 95 upon a curve. Preferably the parts are so formed and arranged that the departure from equilibrium upon a lateral movement of the coupler is substantially the minimum possible to use which will insure the return 100 of the coupler to normal position under any normal conditions of use.
- By my construction, I have provided a supporting arm adapted to swing in one direction in effect upon one axis and adapted 105 to swing in the other direction upon another axis. While I prefer to use this form of device, it will be understood that I do not wish to limit myself to the use of a double-axis construction of this type, except as herein-after specifically claimed, the essential feature being that, upon the swinging of the arm actuated by the lateral movement of the coupling-device, the parts shall be so disposed by such lateral movement that they shall tend to bring the coupler back to its 110 normal position. It accordingly follows that I do not wish to restrict myself to a construction involving the intermeshing engagement between the arms 16-17 and the carrier-iron for holding the arms in proper 115 position relative to the carrier-iron during the swinging movement of the arm, except as hereinafter specifically claimed.
- 120 While I have shown a bearing-plate interposed between the supporting arms or cams 16-17 and the coupling-device so that the coupling-device is effectively supported by such arms through the medium of the bearing-plate, and have shown two supporting 125 130

arms, each of which remains during each complete swinging operation in effective engagement with the coupling-device, it will be understood that I do not wish to limit 5 myself to these particular details of construction except as hereinafter specifically claimed.

That which I claim as my invention, and desire to secure by Letters Patent, is,—

10 1. The combination of a car-body, a coupling-device movable laterally relative to said car-body, and an arm below said coupling-device adapted to swing laterally toward either side of the car-body and adapted 15 to be during its entire swinging movement in effective engagement with said coupling-device for supporting the coupling-device, said arm having its engaging upper end so curved relative to the axis about which it 20 swings that the effective bearing point as said arm swings toward one side of the car-body is shifted slightly toward the opposite side of the car-body relative to the said axis whereby there is a tendency of the coupling-device 25 to return to its normal position.

2. The combination of a car-body, a coupling-device movable laterally relative to said car-body, and an arm below said coupling-device in effective supporting engagement therewith, said arm being adapted to swing laterally toward either side of the car-body, swinging in one direction from normal position upon one axis and swinging in the opposite direction from normal position 30 upon another axis parallel with said first-named axis, said arm having its engaging upper end so curved relative to the axes about which it swings that the effective bearing point as said arm swings on one axis toward one side of the car-body is shifted slightly toward the opposite side of the car-body relative to the said axis whereby there 35 is a tendency of the coupling-device to return to its normal position.

45 3. The combination of a car-body, a coupling-device movable laterally relative to said car-body, a carrier-iron extending laterally beneath said coupling-device, and a supporting member having a plurality of supporting lugs the lower ends of which have intermeshing engagement with said carrier-iron, said supporting member having effective engagement with said coupling-device for supporting the coupling-device, 50 said supporting member being adapted to swing laterally upon one or another of said lugs and having its engaging upper end so curved relative to the axis upon which it swings toward either side of the car-body that upon such a stroke of the said supporting member the bearing point is shifted 55 slightly toward the opposite side of the car-body relative to the said axis whereby there is a tendency of the coupling-device to return to its normal position.

4. The combination of a carrier-iron, a coupling-device movable laterally relative to the carrier-iron, an arm swingingly mounted on said carrier-iron below said coupling-device in effective supporting engagement with 70 the coupling-device, said arm being adapted to swing laterally in one direction upon one axis and in the opposite direction upon another axis, and a pin mounted in said carrier-iron working in a guide provided by 75 said arm for holding said arm in proper engagement with the carrier-iron.

5. The combination of a carrier-iron, a coupling-device movable laterally relative to the carrier-iron, an arm swingingly mounted 80 on said carrier-iron below said coupling-device in effective supporting engagement with the coupling-device, said arm being adapted to swing laterally in one direction upon one axis and in the opposite direction upon another axis, and a pin mounted in said carrier-iron working in a double arcuate slot 85 provided in the arm for holding said arm in proper engagement with the said carrier-iron.

90 6. The combination of a carrier-iron, a coupling-device movable laterally relative to said carrier-iron, an arm mounted on said carrier-iron below said coupling-device in effective engagement with the coupling-device, said arm being provided with two supporting lugs on its lower end adapted to straddle a bearing-rib carried by said carrier-iron and said arm being adapted to swing toward either side upon the supporting lug at that side of the arm, and interengaging guides carried by said arm and said carrier-iron adapted to permit the swinging of said arm but to prevent the operative supporting lug from slipping out of 100 its engagement with the carrier-iron adjacent to the bearing-rib.

110 7. The combination of a carrier-iron, a coupling-device movable laterally relative to said carrier-iron, an arm mounted on said carrier-iron below said coupling-device in effective engagement with the coupling-device, said arm being provided with two supporting lugs on its lower end adapted to straddle a bearing-rib carried by said carrier-iron and said arm being adapted to swing toward either side upon the supporting lug at that side of the arm, and a pin 115 mounted in said carrier-iron engaging a double arcuate slot provided in said arm about the axis upon which said arm is adapted to swing, said pin being adapted to prevent the operative engaging lug from slipping out of its engagement with the carrier-iron adjacent to the bearing-rib.

120 8. The combination of a car-body, a carrier-iron mounted thereon, a coupling-device movable laterally relative to said car-body, two arms below said coupling-device adapted to swing laterally toward either side of 130

- the car-body, a bearing-plate supported by said arms in contact with said coupling-device, means for causing said bearing-plate to move laterally of the car-body with said coupling-device, connections between said bearing-plate and said arms whereby said arms are caused to swing in unison, and means for connecting said bearing-plate with said carrier-iron comprising a pin carried by one of said parts working in a suitable slot in the other part adapted to hold the parts together but to permit free lateral movement of the bearing-plate relative to the carrier-iron.
9. The combination of a car-body, a carrier-iron mounted thereon, a coupling-device movable laterally relative to said car-body, two arms below said coupling-device adapted to swing laterally toward either side of the car-body, a bearing-plate supported by said arms in contact with said coupling-device, means for causing said bearing-plate to move laterally of the car-body with said coupling-device, connections between said bearing-plate and said arms whereby said arms are caused to swing in unison, and a pin mounted in said carrier-iron working in an angular slot in the bearing-plate adapted to hold the parts together but to permit free lateral movement of the bearing-plate relative to the carrier-iron.

THOMAS N. RUSSELL.
